UNITED STATES PATENT OFFICE

91,273

DESIGN FOR A DRESSER OR SIMILAR ARTICLE

Henry H. Koster, Grand Rapids, Mich.

Application October 28, 1933. Serial No. 49,588

Term of patent 3½ years

To all whom it may concern:

Be it known that I, HENRY H. KOSTER, a citizen of the United States, residing at Grand Rapids, in the county of Kent and State of Michigan, have invented a new, original, and ornamental Design for a Dresser or Similar Article, of which the following is a specification, reference being had to the accompanying drawing, forming part thereof.

In the drawing:

Figure 1 is a front elevation of the article, showing my new design,

Figure 2 is a top plan view, and

Figure 3 is an end elevation.

In the drawing the cross hatching represents brown or the mahogany woods and the plane surfaces upon the figures represent white or the maple woods employed.

The dominant feature of the design resides in the contrasting effect made possible by the arrangement of the maple and mahogany woods employed, as shown upon the drawing.

I claim:

The ornamental design for a dresser or similar article, as shown and described.

HENRY H. KOSTER.
